UNITED STATES PATENT OFFICE.

JOSEF ZÄNGL, OF MUNCHEN, GERMANY.

VULCANIZING APPARATUS.

Application filed May 22, 1925. Serial No. 32,092.

This invention relates to a vulcanizing apparatus by means of which repairs of tires, protecting covers and the like can be rapidly and perfectly made.

5 The invention is characterized in that with a heating vessel, of for instance rectangular cross section, all apparatus and auxiliary means are connected which are necessary for vulcanization so that the transportable apparatus can be placed on any convenient source of heat or may be fitted with such a source of heat.

10 Two embodiments of the invention are shown, by way of example, in the according drawing in which:—

Fig. 1 shows in side elevation an apparatus of preferred construction.

Fig. 2 is a plan view of Fig. 1.

20 Fig. 3 shows in side elevation an apparatus of modified construction.

Fig. 4 is a plan view of Fig. 3.

25 A small sized heating vessel *a*, preferably of rectangular shape (Figs. 1 and 2) and made from cast steel, has at the rear side a lug *b* in which a bearing bracket, composed of two parts, is pivotally fixed, the arm *c* of which carries a pressure screw *d* having a hand wheel *e*. The front arm *f* of the bracket is hingedly mounted at *g* on an arm *c* and forms at its end a hook *h*. Arm *f* forms a latch bar, whose hooked end *h* is engageable under a rigid latch lug *i* on the front side of the vessel *a*, whereby the arm *c* is held fixed and against movement when the member *d* is in use to clamp an object. Upon swinging arm *f* outwardly the arm *c* is free to be moved on its pivotal connection, as will be readily understood. A tubular inlet *k* is mounted on the rear side of the vessel laterally of the arm *c* of the bracket. The tubular outflow *l* may be mounted on the right or left side of vessel *a*.

30 The rear corner of the vessel *a* is bevelled and on it a safety valve *m* is mounted by means of a tube *n* on the upper portion of the wall of the vessel, a tube *o* of a manometer *p* being fixed on the lower portion of this bevelled part.

35 In the second form of construction of the apparatus, shown in Figs. 3 and 4 the heating vessel *a* is somewhat wider. It has, lat-

erally of the middle line of the rear wall, two lugs *b* in which the bearing brackets *c* for the pressure spindles *d*, *e* are rotatably mounted. The bearing brackets *c* are 55 hingedly connected, in a similar manner as in Figs. 1 and 2, with an arm *f*, *g*, *h*.

The tubular inflow *k* is arranged between the lugs *b*. *l* is the tubular outflow. The safety valve *m* is mounted on the top plate 60 of the heating vessel between the pressing spindles. The manometer *p* is situated at the side of the tubular inflow the tube *o* of the manometer opening into the lower portion of the heating vessel.

65 The vessel *a* has, as shown in Fig. 3, feet *g* designed to carry the heating device.

The apparatus might also be placed on any convenient source of heat, gas cooker, spirit oven or kitchen range. A source of 70 heat of any convenient type might further be permanently connected with the apparatus.

The apparatus is ready for use, easy to manipulate and constructed in such a manner that burning of the works, whether they are of small size or of large size is excluded.

I claim:—

1. A vulcanizing apparatus comprising a heating vessel of rectangular form and having a top plate, a pivot lug at the rear side of said vessel, an arm having an upright portion journaled at its lower end in said pivot lug and a horizontal portion rigid with said upright portion and overhanging 80 the top plate of the vessel, said horizontal portion of the arm terminating at its free end substantially in alignment with the front side of the vessel, a clamping screw carried by said horizontal portion of the arm for coaction with said top plate, and a releasable latch connection between the front side of the vessel and the overhanging free end of the horizontal portion of said arm.

2. A vulcanizing apparatus comprising a heating chamber of rectangular formation and having a top plate, a pivot lug at the rear side of said chamber, a latch lug at the front side of said chamber, an arm having an upright portion journaled at its lower end in said pivot lug and having a horizontal portion rigid with said upright por-

tion, said horizontal portion extending above the top plate of the chamber and terminating at its free end substantially in alignment with the front side of said chamber, a
5 clamping screw carried by said horizontal portion of the arm for coaction with the top plate, and a latch member pivoted at its

upper end to the free end of the horizontal portion of the arm and having a hooked lower end adapted to engage under the latch 10 lug at the front side of the vessel.

In testimony whereof I affix my signature.

JOSEF ZÄNGL.
